UNITED STATES PATENT OFFICE.

JOHN MURRAY, OF MOUNT VERNON, MINNESOTA, ASSIGNOR OF NINETY ONE-HUNDREDTHS TO ANDREW GREDEN, OF MOUNT VERNON, MINNESOTA.

GUIDE-PULLEY.

1,091,007.

Specification of Letters Patent.

Patented Mar. 24, 1914.

Application filed May 14, 1913. Serial No. 767,628.

To all whom it may concern:

Be it known that I, JOHN MURRAY, a citizen of the United States, residing at the town of Mount Vernon, in the county of Winona, State of Minnesota, have invented certain new and useful Improvements in Guide-Pulleys; and I do hereby declare the following to be a full, clear, and exact description of the invention, such as will enable others skilled in the art to which it appertains to make and use the same.

This invention relates to improvements in guide pulleys for use in connection with hoisting ropes.

15 The invention has for its object to provide a guide pulley so constructed that it will effectually guide and prevent tangling of the hay sling hoisting rope.

20 A further object of the invention is to provide a guide pulley especially designed for use in round barns wherein it is necessary that the hoisting rope which leads from the hay sling frame be guided as the frame of the sling travels upon the circular track 25 therefor.

With these and other objects in view this invention resides in the novel features of construction, formation, combination and arrangement of parts to be hereinafter more 30 fully described, claimed and illustrated in the accompanying drawing, in which:—

Figure 1 is a partial sectional view taken through a round or circular barn, showing the manner in which the pulleys are arranged therein. Fig. 2 is a sectional view 35 showing one of the pulleys applied. Fig. 3 is a side elevation of one of the pulleys. Fig. 4 is a detail perspective view of the pulley frame. Fig. 5 is a top plan view of 40 one of the devices. Fig. 6 is a fragmentary view showing one of the pulleys applied.

Referring to the drawing, the numeral 1 designates a section of a circular barn having the interior studs 2 and roof rafters 3, 45 the latter serving to support the circular track 4, which is of the usual construction.

To each roof rafter 3 is secured a clevis 5, which serves to support the frame 6, said frame being formed a single length of sheet

metal so bent as to provide upper and lower 50 plates 7 and 8, and between which are rotatably mounted the guide pulleys 9, which may be formed from metal or wood, as desired. The upper plate 7 is partially twisted, as at 10, to provide a vertical plate 11, said 55 plate being formed with a slot 12 for pivotally engaging the clevis 5. The plate 8 terminates at its inner end in a downwardly extending plate 13 which has a curved end 14, so that the hoisting rope 15 will be easily 60 guided to the pulley 9.

Secured to the inner end of the plate 7 of each frame 6 is the lower end of a chain 16, the upper ends of these chains being adapted to adjustably engage the hooks 17 secured to 65 the roof rafters 3, so that said frame can be raised or lowered to different inclined relations with the said rafters.

One end of the hoisting rope 15 is connected to the hay sling frame 18, in the customary manner, said frame being of the usual construction.

From this construction it will be seen that when the free end of the hoisting rope 15 is pulled, the same will be effectually guided 75 and prevented from becoming tangled, as the same passes over the pulleys 9 during the movement of the sling frame 18.

What is claimed is:—

A guide pulley comprising a frame 80 formed from a single length of sheet metal and bent to provide upper and lower spaced plates, a pulley rotatably mounted between the plates, the upper plate being twisted at its inner end to provide a vertically disposed plate which is adapted to be pivotally connected to a support, the lower plate of the frame terminating in a downwardly extending plate, the lower end of which is curved for guiding a rope to the pulley, and 85 a chain for connecting the frame to a support, as and for the purpose set forth.

In testimony whereof, I affix my signature, in the presence of two witnesses.

JOHN MURRAY.
